UNITED STATES PATENT OFFICE.

ISAAC E. PALMER, OF MIDDLETOWN, CONNECTICUT.

DESIGN FOR A HAMMOCK.

SPECIFICATION forming part of Design No. 23,305, dated May 22, 1894.

Application filed April 13, 1894. Serial No. 507,484. Term of patent 14 years.

To all whom it may concern

Be it known that I, ISAAC E. PALMER, of Middletown, in the county of Middlesex and State of Connecticut, have invented and produced a new and original Design for Hammocks, of which the following is a specification, reference being had to the accompanying drawings, forming a part thereof.

The leading feature of my design consists in the shape of the hammock provided with a shorter outer valance extending from the edge of the body of the hammock and a longer or deeper under valance extending from the sides of the hammock, producing flounces at the sides of the hammock, as shown.

Figure 1 represents the appearance of the body and valances when they are spread out in a plane and Fig. 2 represents the appearance which the parts assume when the hammock is strung.

A represents the body of the hammock, a the outer valance of less depth and B the inner deeper valance.

What I claim is—

The design for a hammock, substantially as herein shown and described.

ISAAC E. PALMER.
